UNITED STATES PATENT OFFICE.

ERNEST I. DAUER, OF PROVIDENCE, RHODE ISLAND, ASSIGNOR TO ALBERT WEINER,
OF PROVIDENCE, RHODE ISLAND.

MOUNTING FOR ARTICLES OF JEWELRY.

Application filed June 7, 1927. Serial No. 197,111.

This invention relates to the manufacture of ornamental objects for attachment to chains, bracelets, ear-rings, brooches, necklaces and other articles of jewelry or adornment.

The principal object of the invention is to provide a means for mounting pearls, beads, brilliants or other similar objects in a group or cluster whereby to provide a 10 pendant or ornament for application to the article of jewelry.

A particular object of the invention is to provide a simple, inexpensive mounting, frame or holder having a plurality of projections or arms extending in different directions and adapted to receive the pearls or other objects which are cemented or otherwise secured thereon.

Further objects of the improvement are 20 set forth in the following specification which describes a preferred embodiment of the device as illustrated in the accompanying drawings. In the drawings:

Fig. 1 is a view showing a cluster of pearls 25 or the like supported on my improved frame or mounting in the form of a bunch of grapes;

Fig. 2 is a perspective view showing the general construction and arrangement of the 30 mounting for the pearls or other ornaments;

Fig. 3 is a plan view of the same; and

Fig. 4 is a perspective view showing the two parts of the frame or mounting before they are assembled in cooperative relation.

It is common in the jewelry and kindred arts to mount spherical or globular objects such as pearls, beads, ornamental brilliants or the like in clusters to provide pendants or charms for suspension from other articles.

These clusters may have a general spherical shape or may be of tapering contour in simulation of bunches of grapes. To mount the pearls or other objects in this form it is required to provide a central support or 45 frame on which the objects are assembled and suitably secured in place with the frame or support hidden from view.

In accordance with a preferred form of construction of the invention I provide a 50 support or mounting made from sheet-metal parts which may be stamped or punched out in the form shown in Fig. 4 of the drawings. The two complementary parts 2 and 3 of the frame or mounting may be of 55 the same general structure, each comprising

a central rib or strip 4 from which project lateral prongs or arms 5 made integral therewith. The central rib or strip 4 is preferably reduced in width at one end to form a substantially round or square wire or pin, 60 while its wider portion has a medial slot 6 extending throughout substantially half its length.

For a frame or mounting designed to support pearls or other spherical objects in a 65 tapering cluster, in simulation of a bunch of grapes as herein illustrated, the two members 2 and 3 have a generally triangular outline in plan view. That is to say, the lateral arms 5 are graduated in length from 70 one end of the central rib or strip 4 to the other as shown most clearly in Fig. 4. It will also be noted by reference to this view that whereas the frame-member 2 has its slot 6 at the end with the prongs of shorter 75 length, the other member 3 is slotted at the opposite end having the longer prongs. Likewise, on the member 2 the wire pin 7 projects from the end with the longest prongs while on the member 3 it projects 80 from the end with the shorter prongs, the parts being thus reversed in arrangement with respect to the graduation of the arms or prongs 5.

The two frame-members 2 and 3 are assembled to form the mounting by arranging them in planes at substantially right-angles or perpendicular to each other as shown in Fig. 4 and then sliding one member into interengaging relation with the other member. That is to say, the central rib 4 of one member is entered into the slot 6 of the other member in a sort of telescoped arrangement as shown in Fig. 2 of the drawings. This provides that the slotted portion of one element will straddle the central rib 4 of the other element as the corresponding arms 5 on the two members are brought into alignment. The parts are then soldered or brazed together along the joint between the 90 central ribs 4 and in this way a strong, rigid structure is provided in the form shown in Fig. 2.

The completed frame thus comprises a central rod or vertical spindle from which 105 project at regular intervals a series of lateral arms 5 disposed at substantially right-angles to each other in horizontal planes as illustrated most graphically in Fig. 3 of the drawings. The central rib 4 of each frame- 110

member is reenforced and stiffened by the complementary rib 4 of the other member and the pins 7 and 8 project vertically at either end of the mounting for a purpose 5 as later explained. In general, the frame or mounting has the form and contour of a pine tree reversed in position with its lateral arms or branches radiating from a central trunk and graduated in length from top to 10 bottom.

The ornaments are applied to the ends of the branches or arms 5 of the mounting and in the present drawings I have illustrated them as spherical objects such as beads or 15 pearls 10. The beads or pearls 10 are bored axially to adapt them to be slid onto the arms 5 and cemented thereto in the usual manner to hold them in place. Usually, the pearls 10 are graduated in size with the 20 larger ones placed on the longer arms at the top of the mounting and ranging down to the smaller ones at the bottom. A pearl of the largest size may be impaled on the upper upright wire or pin 7, and one of the 25 smaller size cemented to the shorter bottom pin 8. The upper pin or wire 7 projects through the top of the uppermost pearl 10 and is bent around to form a loop or eye 11 as shown in Fig. 1 of the drawings to 30 provide a suspension or attaching means for the pendant. If desired, a finishing cap or ornament 12 constructed of pierced sheet-metal in the shape of a rosette may be fitted around the surface of the topmost pearl 10 and held thereto by soldering it to the pin 7 below the ring 12.

When the pearls or other ornamental objects are mounted on a frame or support of the type herein illustrated the cluster will 40 assume the contour of a bunch of grapes tapering from top to bottom in more or less regular outline as illustrated in Fig. 1. In other cases the frame or mounting may have its arms or prongs 4 of graduated 45 lengths arranged in different order; for instance, tapered from the center of the spindle toward both ends or designed to give other forms to the complete article.

It will be observed from the above that 50 the invention provides a particularly simple yet rigid and strong construction for the central frame or mounting which carries the ornamental objects supported in a cluster. The frame or mounting comprises 55 only two elements which may be constructed as stampings punched out from sheet-metal in suitable dies so as to provide for economical cost of manufacture. The two parts of the mounting are easily assembled and 60 secured together in fixed relation without

requiring expert workmanship. The whole frame or mounting may thus be manufactured at relatively low cost and the beads or other ornamental objects readily mounted thereon by unskilled workers. My improved device is therefore well adapted for 65 quantity production at economical cost while the completed article has a relatively high value as an object of art or ornamentation. 70

While I have herein described and illustrated a preferred form of construction of the device it is to be understood that modifications may be made in the structure and arrangement of the same without departing 75 from the spirit or scope of the invention. Therefore, without limiting myself in this respect, I claim:

1. A frame or mounting for supporting clusters of ornamental objects, comprising 80 a plurality of members each having a central rib with arms projecting laterally therefrom, said members being secured together in overlying relation with the arms radiating therefrom in angular relation there-around.

2. In a device of the type specified, the combination of a frame or mounting comprising a plurality of members, each having a central longitudinally-slotted rib with 90 arms projecting laterally therefrom and said members assembled with their ribs in inter-engaging overlying relation and secured in position with their arms projecting in different planes intersecting a central axis 95 passing therethrough.

3. In a device of the type described, the combination of a frame or mounting comprising two complementary members having 100 central ribs with longitudinal slots at their ends and arms projecting laterally from their sides, said members held in assembled relation with their slotted ribs interengaging and disposed in opposite planes with their arms radiating from the central axis 105 of the frame.

4. In a device of the type specified, the combination of a frame or mounting comprising two complementary sheet-metal members formed with central flat ribs slotted throughout a portion of their length and provided with laterally projecting arms and pins projecting from their unslotted ends, said members secured in assembled 110 relation with the slot in one rib engaging the unslotted portion of the other rib and their arms projecting laterally in angular 115 relation to each other.

In testimony whereof I affix my signature.
ERNEST I. DAUER.
